UNITED STATES PATENT OFFICE.

DAVID PETRI-PALMEDO, OF HOBOKEN, NEW JERSEY, ASSIGNOR TO ELECTRIC COMPOSITOR COMPANY, OF NEW YORK, N. Y., A CORPORATION OF NEW JERSEY.

SPACE-BAR FOR JUSTIFYING MATRIX-LINES.

1,112,652.

Specification of Letters Patent.

Patented Oct. 6, 1914.

Application filed November 10, 1911. Serial No. 659,500.

To all whom it may concern:

Be it known that I, DAVID PETRI-PALMEDO, a citizen of the United States, residing at Hoboken, in the county of Hudson 5 and State of New Jersey, have invented a certain new and useful Improvement in Space-Bars for Justifying Matrix-Lines, of which the following is a full, clear, and exact description.

10 This invention relates to improvements in expanding space bars adapted for use in justifying lines of assembled matrices preparatory to casting a type bar from said justified line.

15 The object of the invention is to produce such a space bar in a form which costs less and will be more durable in service than the space bars heretofore known.

20 The invention consists in the construction and combination of parts shown, as herein-after set forth and claimed.

In the drawing, Figure 1 is a perspective view of my improved space bar. Fig. 2 is an elevation of one side thereof. Fig. 3 is 25 an elevation of the opposite side. Fig. 4 is an edge view. Fig. 5 is an elevation of the inner side of the fixed wedge member. Fig. 6 is a sectional view thereof in the plane indicated by line 6-6 on Fig. 5. Fig. 7 is a 30 vertical sectional view of Fig. 5; and Figs. 8 and 9 are respectively transverse sectional views of the movable wedge member in the planes indicated by line 8-8 and 9-9 respectively.

35 The space bar consists of two wedge members whose engaging faces are oppositely inclined, but at the same angle, so that their outer faces will be parallel at all times so long as the inner faces are in contact. The 40 fixed member A is intended to occupy a fixed position in the matrix line. It is thickest at its upper edge. It has in its inner face a vertical groove *a* extending from top to bottom, and of uniform depth from end 45 to end. The sides of this groove are undercut or dove-tailed, as shown clearly in Fig. 6.

The member B is the movable member and is thickest at its lower end. It has on 50 its inner face a tongue or rib *b* which extends from top to bottom, and is undercut or dove-tailed; and, when the parts are assembled, as shown, fits nicely within the groove *a*, but permits the member B to move relatively to the member A. This rib not 55 only acts to hold the two parts in proper

relative position and to permit the member B to move relatively to the member A, but it also reinforces the member B and thereby greatly strengthens it. This added strength is of great value because this member B is 60 subject to considerable pressure against its lower end to move it upward when a line is being justified; and this added strength produced by this rib will enable the member B to stand this pressure without danger of being bent in actual service. Space bars whose movable depending member has its central part cut out are frequently bent in practice, and thereby the space bar, for the time being, at least, becomes useless. After these 65 two parts A and B have been assembled as described, the pins *b*³, *b*², are driven into the member B, and are adapted to engage respectively with the top of the member A and the bottom thereof. There is a notch 70 *a*² cut in the top of the member A and the pin *b*² goes into it when the upper ends of the two members A and B are alined.

There are two laterally projecting ears *a*³ 75 at the lower end of the member A. These 80 serve to be engaged by their upper edges by bars or the like to prevent the upward movement of the member A when the member B is being pushed up for the purpose of expanding the space bar. These ears are 85 considerably thicker than the thickness of the thin lower edge of member A, and preferably their thickness is equal to the thickness of the thick upper end of said member A. The outer surfaces of these ears are in the 90 same plane as the outer vertical surface of the member A; wherefore since they are thicker than the thin part of member A, from which they project, they extend along-side of both edges of the wedge bar B, and 95 thus supplement the tongue *b* and groove *a* in guiding the wedge bar B in its required straight path. It will be noticed that there are no other lateral projections or indentations in the edges of these two members of 100 the space bar; and this enables these space bars to be produced more economically than if there were a plurality of such lateral projections or indentations as has been common heretofore in space bars.

Having thus described my invention, I 105 claim:

1. An expansible space bar for justifying matrix lines, comprising a body wedge member and a relatively movable wedge bar of 110

equal width,—said body wedge member having a vertical outer face and an inner face which is inclined toward the outer face from top to bottom, said inner face having formed 5 in it and extending from top to bottom a dove-tailed groove of like depth from end to end,—and the wedge bar having a vertical outer face and an inner face which is inclined toward the outer face from the lower 10 end to the upper end of said wedge bar,—there being formed on the inner inclined face of said wedge bar a projecting dovetailed rib which is of equal thickness from end to end and is slidably fitted in the groove in 15 the inclined face of the body wedge member, said wedge bar having two pins fixed to it and projecting respectively over and under the body wedge member, the wedge bar being devoid of lateral projections and the 20 body wedge member having no lateral projections except that it has two ears which project laterally at the lower edge thereof.

2. An expandible space bar for justifying matrix lines comprising a body wedge member and a relatively movable wedge bar of 25 equal width, said body wedge member having a vertical outer face and having an inner

face which is inclined toward the outer face from the top to the bottom thereof, said inclined inner face having formed in it and extending from top to bottom of said member a dovetailed groove of like depth from end to end, and said body member having projecting sidewise from both of the lower thin edges of said body member ears which are 30 thicker than the thickness of said thin lower end of the wedge member, said ears being arranged with their outer surfaces in the same plane with the outer vertical surface of said body member,—and the wedge bar having a 40 vertical outer face and an inner face which is inclined toward the outer face from the lower end to the upper end of said wedge bar,—there being formed on the inner face of said wedge bar a projecting dovetailed 45 rib which is of equal thickness from end to end and is slidably fitted in the groove of the inclined face of the body wedge member.

In testimony whereof, I hereunto affix my signature in the presence of two witnesses. 50

DAVID PETRI-PALMEDO.
